SPRAY GUN FOR WATER AND SOLUBLE PRODUCTS

Larry N. Lesley, 6206 Llano, Dallas, Tex. 75214, and
Donald G. Ray, 818 W. Shady Grove, Irving, Tex.
75060

Filed July 18, 1967, Ser. No. 7,861

Term of patent 14 years

(Cl. D23—17)

FIG. 1

FIG. 2

FIG. 3

FIG. 4

FIGURE 1 is a top plan view of the spray gun for water and soluble products of this invention.

FIGURE 2 is a side elevational view of the device shown in FIGURE 1.

FIGURE 3 is an elevational view of the side opposite to that shown in FIGURE 2.

FIGURE 4 is a front elevational view of the device shown in FIGURES 1-3.

The bottom and rear views are plain (without ornamentation).

We claim:

The ornamental design for a spray gun for water and soluble products, as shown and described.
